UNITED STATES PATENT OFFICE.

AMOS S. HAYDEN, OF HOLBROOK, MASSACHUSETTS, ASSIGNOR TO UNITED SHOE MACHINERY CORPORATION, OF PATERSON, NEW JERSEY, A CORPORATION OF NEW JERSEY.

FLUID-APPLYING MACHINE.

1,376,538.

Specification of Letters Patent.

Patented May 3, 1921.

Application filed August 11, 1919. Serial No. 316,819.

To all whom it may concern:

Be it known that I, AMOS S. HAYDEN, a citizen of the United States, residing at Holbrook, in the county of Norfolk and State of Massachusetts, have invented certain Improvements in Fluid-Applying Machines, of which the following description, in connection with the accompanying drawings, is a specification, like reference characters on the drawings indicating like parts in the several figures.

This invention relates to machines for applying fluids. The machine of the invention is particularly adapted for the application of blacking and other stains to the edges of the soles of shoes, being herein shown in connection with the sole-blacking machine which is disclosed in a Patent No. 1,311,161, issued in the name of F. M. Furber, July 29, 1919. In sole-blacking apparatus of this type the coating fluid, in the form of a spray, is delivered upon the upper edge portion of a sole positioned horizontally by an edge-rest at one side, this being, in the present instance, the supply or suction conduit of the machine, and positioned vertically with respect to its distance from the spray nozzle by a gage, which also serves as a guard to protect from the spray the adjacent surface of the sole which is to remain uncoated.

An object of the invention is to provide for an alteration in the width of the coated area. This I attain by means arranged to vary the position of the work transversely to the direction of spray delivery, as by an edge-rest adjustable in its relation to the source of spray and holding the work spaced therefrom. This rest I prefer to arrange about the supply conduit. It being shown as consisting of an eccentric sleeve with means for fixing it in different positions. An organization of this character furnishes members contacting with the work at opposite sides of the spray-delivering means, one member being the edge-rest, and the other the combined gage and guard, which members are relatively adjustable transversely of the spray.

In fluid-applying machines employing a spray, the extension into the path of said spray of elements of the machine tends to divert it from the proper course or to gather it into drops which will be thrown into the

air to be wasted and possibly cause injury to surrounding objects or to the operator by their inhalation. To prevent the position-varying means from producing such effects is another object of the invention, and to this end I locate the means for fixing the position-varying means out of the path of the spray. With the rest carried upon the supply conduit, the position-determining means therefor may be adjacent to the applying device. Since, when a spray nozzle is employed, a point thus located will be near the narrower portion of the jet before it spreads laterally in its passage toward the work, the position-determining means may readily be kept clear of the fluid.

In the accompanying drawing, illustrating one form of my invention,

Figure 1 is a side elevation of a portion of a sole-blacking machine embodying my invention, parts being in section; and

Fig. 2 is a perspective view illustrating the work in contact with the positioning means, and including a portion of the nozzle.

The numeral 10 designates a portion of the supporting frame of a sole-blacking machine, this frame carrying a hollow arm 12, to which is connected a source of air pressure. The air is delivered from the arm to an outlet tube 14 of an atomizing or spray-producing device carried by a head 16 mounted upon the outer extremity of the arm. The head has delivering to it a supply or suction pipe or conduit 18 rising from a fluid receptacle 20 supported upon the frame, and having at its lower end the usual strainer 22. The opening at the upper extremity of the conduit 18 delivers to a horizontal mixing passage 24, into which the outlet tube 14 projects. In the under side of the head, in alignment with the nozzle 14, is a delivery opening 26. This spray-producing device operates in the usual manner of atomizers, the air blast issuing through the opening of the nozzle 14 and passing through the delivery opening 26, producing a suction through the conduit 18 which raises the coating fluid from the receptacle into the mixing chamber, from which it is carried by the air blast as a spray through the delivery opening 26.

Secured to the outer side of the head 16 by a screw 28 is a gage-plate 30, the lower

edge of which is separated from the adjacent side of the conduit 18 by a distance approximating the width of the space which it is desired to coat upon the sole. Preferably the screw 28 passes through a vertical slot 31 in the plate 30, thus enabling the operator to change the distance of the lower edge of the plate from the delivery opening and consequently the force with which the spray strikes the work. This plate is also extended in the direction of advance of the work, and is so related to the opening 26 that it protects the inner area of the sole operated upon from the spray, thus preventing waste of the coating fluid.

Opposite the gage 30, about the conduit 18, is a sleeve 32, shown as fitting it to turn thereon, but being at its exterior eccentric to the surface of said conduit. The amount of this eccentricity should be substantially equal to the variation which it is desired to produce in the width of the coated area of the sole. The sleeve may be fixed in position by a screw 34 threaded through its wall, preferably at the thicker side, to give proper engagement for the screw threads, and at or near the upper extremity of the sleeve. The length of the screw may be such that its head is substantially flush with the exterior of the sleeve. Thus located, it is entirely clear of the path of the spray, regardless of the angle through which the sleeve is turned, since it is adjacent to the point at which the jet issues from the delivery opening 26 in its most contracted form. If the screw or position-determining device were situated near the bottom of the sleeve, or projected much beyond its surface when turned toward the gage 30, it might be struck by the spray, causing this to spatter and waste. It might also interfere with the application of the work to the rest. With my arrangement there is presented to the spray and the work only the smooth, unbroken exterior of the adjusting sleeve. It will be obvious, that by loosening the screw 34 and turning the sleeve about the conduit, the surface which by its contact with the sole edge determines the position transversely of the path of the spray, will be changed, so that the band of coating produced may, within the limits of the thickness of the sleeve wall, be of any desired width.

Having described my invention, what I claim as new and desire to secure by Letters Patent of the United States is:—

1. In a machine of the class described, spray-delivering means spaced from the surface against which the spray is directed, and means arranged to vary the position of the work transversely to the direction of spray delivery.

2. In a machine of the class described, spray-delivering means spaced from the sur-

face against which the spray is directed, a gage situated at one side of the spray-delivering means, and a work-rest movable toward and from the gage.

3. In a machine of the class described, spray-delivering means, members for contact with the work at opposite sides of the spray-delivering means, and means arranged to vary the relative position of said members transversely to the direction of spray delivery.

4. In a machine of the class described, spray-delivering means, members for contact with the work at opposite sides of the spray-delivering means, means arranged to vary the position of one of said members in the direction of spray delivery, and means arranged to vary the position of the other member transversely to the direction of spray delivery.

5. In a machine of the class described, spray-delivering means spaced from the surface against which the spray is directed, a guard for the work situated at one side of the spray-delivering means, and a work-rest variable in position at the opposite side of the spray-delivering means from the guard and independently thereof.

6. In a machine of the class described, spray-delivering means spaced from the surface against which the spray is directed, and a work-rest variable in position with respect thereto.

7. In a machine of the class described, a fluid-applying device, a conduit delivering thereto, and a work-rest mounted to move upon the conduit.

8. In a machine of the class described, a fluid-applying device, a conduit delivering thereto, and a work-rest variable in position about the conduit.

9. In a machine of the class described, a fluid-applying device, a conduit delivering thereto, a work-rest mounted upon the conduit, and means arranged to vary the position of the work-rest upon the conduit.

10. In a machine of the class described, a fluid-applying device, a conduit delivering thereto, an eccentric sleeve surrounding the conduit, and means arranged to fix the sleeve in different positions.

11. In a machine of the class described, a spray nozzle, a suction conduit therefor, and a work-rest surrounding the suction conduit and variable in position thereon.

12. In a machine of the class described, a spray nozzle, a suction conduit therefor, and an eccentric sleeve surrounding the suction conduit adjacent to the nozzle.

13. In a machine of the class described, a spray nozzle, a suction conduit therefor, an eccentric sleeve surrounding the suction conduit adjacent to the nozzle, and a screw threaded through the sleeve for engagement with the conduit.

14. In a machine for applying fluid to soles, a fluid spray device, a rest for contact with the edge of a sole adjacent to the spray device and arranged to hold said sole spaced from said spray device, and means arranged to vary the relation of the sole-engaging surface of the rest to the spray device.
15. In a machine of the class described, spray-delivering means, means arranged to vary the position of the work transversely to the direction of spray delivery, and means located out of the path of the spray and arranged to determine the adjustment of the position-varying means.
16. In a machine of the class described, a fluid-applying device, a conduit delivering thereto, a work-rest mounted upon the conduit, and means located adjacent to the applying device and arranged to determine the position of the work-rest upon the conduit.
17. In a machine of the class described, a fluid-applying device, a conduit delivering thereto, a work-rest mounted upon the
14. In a machine for applying fluid to soles, a conduit, and means engaging the conduit adjacent to the applying device and arranged to determine the position of the work-rest upon the conduit.
18. In a machine of the class described, a fluid-applying device, a conduit delivering thereto, a work-engaging sleeve surrounding the conduit, and means located adjacent to the applying device for securing the sleeve to the conduit.
19. In a machine of the class described, a fluid-applying device, a conduit delivering thereto, a work-engaging sleeve surrounding the conduit, and a screw threaded through the sleeve and engaging the conduit adjacent to the applying device.
20. In a machine of the class described, a fluid-applying device, a conduit delivering thereto, an eccentric sleeve surrounding the conduit, and a screw threaded through the thicker wall of the sleeve and engaging the conduit.

In testimony whereof I have signed my name to this specification.

AMOS S. HAYDEN.
